CARBURETOR

Jay S. Culp, Detroit, Mich., assignor to Monarch Governor Company, Detroit, Mich., a corporation of Michigan

Application May 19, 1930, Serial No. 453,705

17 Claims. (Cl. 261—34)

The invention relates to carburetors and consists in various novel features of construction as hereinafter set forth.

In the drawings:

5 Figure 1 is a vertical central section through my improved carburetor showing the parts in idling position;

Figure 2 is a side elevation partly in section;

Figures 3 and 4 are views similar to Figure 1 10 showing parts in different positions of adjustment;

Figure 5 is an elevation viewed at right angles to Figure 2, and

Figure 6 is a section on line 6—6 of Figure 2.

15 As shown in Figure 1, A is a casing section attached to the engine inlet manifold and containing a butterfly throttle valve B and a Venturi passage C on the atmospheric side of the throttle.

D is a bell shaped casing section surrounding the 20 casing A and E is a tubular casing depending centrally within the casing D and extending into the casing A to a point slightly beyond the restricted throat of the venturi. The upper portion E' of the casing E forms a fuel storage chamber

25 and the barrel of a pump. Fitting within this barrel is a cup shaped piston F which is arranged adjacent to a head G loosely fitting the barrel. The head G has a tubular stem H in the upper portion of which is arranged the stem I of a

30 needle valve J. In the lower portion of the stem H which passes through a clearance aperture in the piston F is slidably arranged a tube K, the upper end of which cooperates with a needle valve to restrict the area of the passage. Sur-

35 rounding both the stem H and the tube K is a sleeve L which slidably fits within the casing E and at its lower end is provided with obliquely directed spray apertures L' and a central downwardly directed aperture L². The sleeve L is

40 mechanically connected to the throttle through the medium of a tubular link M having spherical ends M', M² which respectively engage sockets in the lower end of the sleeve L and upon the throttle B at one side of its axis. The shank I of

45 the needle valve is attached to a supporting member N which is within a hollow cap O having a threaded engagement with the upper end of the casing D and a spring P is interposed between the member N and the head G to resiliently press the

50 former upward and the latter downwardly. A fuel supply line Q is attached to the cap O.

With the parts as thus far described, it will be understood that the liquid fuel from any suitable source such as a gravity feed line or a pump line

55 is free to enter through the conduit Q into the

space within the hollow cap O and past the loose fitting head G to the cup shaped piston F. This piston is normally slightly separated from the head G resting upon the upper end of the sleeve L by the resting of the lower end of the tubular stem H on the bottom of the recess in the member L and in this position there is an open passage for the fuel between the head G and the piston and through the clearance between said piston and stem H into a clearance space R between said sleeve and the tubular stem H. This tubular stem H has a series of apertures S therein permitting the fuel to pass from the space R into this hollow stem H and thence past the needle valve into the tube K. From the latter the fuel can pass downward whenever there is any pressure which is in excess of atmospheric pressure, but when the engine is running atmospheric pressure will prevent discharge of fuel through the obliquely arranged jet openings L'. 60

When the parts are in the position shown in Figure 1, that is, where the throttle is substantially closed or in idling position, the tubular connecting rod M will convey fuel from the tube K downward to the throttle and through a registering port T in the latter into the engine intake. Thus in starting the suction within the intake due to the cranking will draw fuel through the tubular rod M and port T into said intake. The liquid fuel may also be commingled with air which 65

is drawn in through the oblique jet apertures L' thereby forming an emulsion which in the intake is commingled with more air to form a combustible mixture. As soon, however, as the throttle is turned from its idling to a more open 70

position as illustrated in Figure 3, the rocking of the ball M² in its socket will cut off communication between the tubular rod M and port T so that all of the fuel will be discharged through the inclined ports L'. This movement of the 75

throttle will also draw the sleeve downward which by withdrawing its support from the cup-shaped piston F will permit the spring P to force the head G downward carrying with it the piston and placing a positive pressure on the liquid fuel with- 80

in the chamber E'. Thus the fuel will be dis- charged under a head developed by the ten- sion of the spring P and through an aperture 85

controlled by the needle valve J, said aperture being enlarged as the throttle is opened. During 90 this downward movement of the head G and piston F the head will be pressed against the

piston so that an annular bearing G' on the head will seal against the piston and prevent any

leakage of the fuel upward. Thus the cup, head 95

100 piston F and sleeve L will be held in the closed position.

During the downward movement of the head G and piston F the head will be pressed against the

piston so that an annular bearing G' on the head will seal against the piston and prevent any

leakage of the fuel upward. Thus the cup, head 105

110 piston F and sleeve L will be held in the closed position.

and sleeve together function as a check valve, permitting the fuel to pass downward by the piston when the throttle is in idling position by preventing any return movement of the fluid past 5 the piston when the latter is drawn downward. The ball M^2 also functions as a valve which opens communication from the fuel line to the manifold when the throttle is in idling position and closes this communication when the throttle is partly 10 open.

In operation, the hood D functions as a flame arrester as it causes any back-fire flame to reverse its direction and to discharge downward. The hood also has the beneficial effect of a dust 15 mover by causing an initial upward movement of a current of air before it can enter the intake. As the open area of the hood is considerably in 20 excess of the open area of the casing A the velocity of the upward current of air will be correspondingly slower than that of the descending air current which also will tend to separate out the dust. Normally the fuel is held from 25 discharge by atmospheric pressure but as soon as the engine is started fuel is discharged either through the throttle when the latter is in idling position or through the jet apertures L' when the throttle is partly opened. The amount of discharge is regulated by the needle valve J and to 30 permit of adjustment in the setting of this needle valve the casing D which carries the stem I of the valve is adjustable with respect to the casing A. This is preferably accomplished by a screw bolt U which passes through a bearing in the casing D and engages a threaded socket in the member A. A spring V in a recess in the member D and bearing at one end against said member and on the other hand against the member A serves to separate these members whenever the 35 screw U is adjusted to permit such separation. The casing V is held from rotation about the bolt U by a lug W on the casing A which engages a groove guide on the casing D. Thus the turning of the screw U so as to raise the casing D would 40 enlarge the area of the opening past the needle valve while an adjustment of said screw in the opposite direction will restrict such area.

For adjusting idling position of the throttle the throttle stem or rock shaft B' has mounted thereon an arm B^2 provided with an adjusting 45 screw B^3 for engaging a stop Z on the casing A. Thus by adjusting this screw the degree of closing of the throttle for idling position will be regulated.

It will be noted that while the connection between the throttle and the piston is non-positive, the connection between the piston and tube K which co-operates with the needle valve is positive. Thus while the throttle may be quickly opened, the restriction to the flow of fuel by the 55 needle valve is not removed until there is positive displacement of the piston by the spring P and the greater the displacement of the piston the larger the opening for the flow of fuel. This insures development of sufficient pressure on the 60 liquid fuel to produce a proper spray.

While I have described the nozzle as arranged to discharge downwardly, it is obvious that the operation of the carburetor is not dependent upon this for it would still be operative if reversed in 65 position or arranged at any different angle.

What I claim as my invention is:

1. In a carburetor, the combination with a downwardly directed mixture inlet having a manually controlled throttle therein, of a nozzle 70 extending downwardly into said inlet, a mov-

able section at the lower end of said nozzle, a needle valve cooperating with said movable section to control the discharge of fuel, and a connecting rod between the throttle and said movable section whereby the latter is opened by the 75 former.

2. In a carburetor, the combination with a downwardly directed throttle controlled mixture inlet, of a vertically adjustable fuel nozzle extending downward into said inlet, fuel metering 80 means controlled by the movement of said nozzle, a hollow connecting rod between the throttle and said nozzle to actuate the latter from the former and also constituting a fuel passage from said nozzle to a port through said throttle in the 85 idling position of the latter, said port being closed by the angular movement of said rod when the throttle is open.

3. In a carburetor, the combination with a downwardly directed mixture inlet, of a butterfly throttle valve controlling said inlet, a fuel nozzle extending downward into said inlet, a hollow connecting rod between said throttle and fuel nozzle for vertically adjusting the latter by the movement of the former, said rod forming 95 a fuel passage from said nozzle which in the closed position of the throttle registers with a port therethrough, said rod and throttle also constituting a valve for closing said port by their relative angular movement during the 100 opening of the throttle.

4. In a carburetor, the combination with a downwardly directed mixture inlet, of a throttle valve in said inlet, a vertically adjustable fuel nozzle extending downward into said inlet and 110 provided with a central discharge port and one or more laterally directed discharge ports, a hollow connecting rod forming a mechanical connection between said throttle and said nozzle for actuating the latter by the former and also 115 constituting a fuel passage from said central port to a port through said throttle in the idling position of the latter, said port through the throttle being closed by the relative angular movement of said rod when said throttle is open 120 whereby fuel is discharged from said nozzle through the throttle in idling position and is directed laterally into said mixture inlet in the open position of the throttle.

5. In a carburetor, the combination with a 125 downwardly directed mixture inlet, of a throttle valve in said inlet, a vertically movable nozzle extending into said inlet above said throttle, a connection between said throttle and nozzle for actuating the latter from the former and 130 means automatically operating a plunger adapted to move downward upon the lowering of said nozzle to eject fuel therefrom.

6. In a carburetor, the combination with a downwardly directed mixture inlet, of a throttle valve controlling said inlet, a nozzle extending downward into said inlet, a fuel reservoir, a plunger for ejecting fuel therefrom through 135 said nozzle, a vertically movable member at the lower end of said nozzle, a hollow connecting 140 rod between said member and said throttle for actuating the former by the latter, and for holding said member in the idling position of the throttle so as to constitute a stop preventing movement of said plunger, said hollow rod constituting a fuel passage from said nozzle to a 145 port through said throttle in said idling position and cutting off communication between said port and said nozzle when the throttle is open 150

- whereby the opening of the throttle will permit said plunger to eject fuel from said nozzle.
7. A carburetor comprising a downwardly directed mixture inlet, a throttle valve therein, a casing extending downward into said inlet and having a fuel reservoir portion and a nozzle receiving portion, a plunger in said reservoir portion for ejecting fuel therefrom, a nozzle in said nozzle receiving portion normally holding said plunger from operation and a mechanical connection between said throttle and nozzle for lowering the latter upon the opening of the former whereby said plunger is permitted to function to eject fuel.
- 15 8. In a carburetor, the combination with a downwardly directed mixture inlet, of a throttle valve therein, a bell shaped housing covering and overlapping said mixture inlet, a hollow centrally depending portion through said housing extending into said mixture inlet and constituting a fuel reservoir and a nozzle support, a nozzle vertically adjustable within said nozzle support, a mechanical connection between said throttle and nozzle for actuating the latter from the former, and a pump plunger in said reservoir automatically actuating upon the movement of said nozzle to eject fuel therethrough.
- 20 9. A carburetor comprising a downwardly directed mixture inlet, a throttle valve controlling the same, a casing above said inlet having a cylindrical barrel portion and a portion of reduced diameter depending therefrom into said inlet, a piston in said barrel, a spring for yieldably pressing said piston downward, a nozzle telescopically engaging the portion of reduced diameter and forming a stop for said piston and a mechanical connection for depressing the nozzle upon the opening of the throttle, thereby withdrawing the stop and permitting the spring 35 pressed piston to eject fuel from said nozzle.
- 30 10. A carburetor comprising a downwardly directed mixture inlet, a throttle valve controlling the same, a casing above said inlet having a cylindrical barrel portion and a portion of reduced diameter depending therefrom into said inlet, a piston in said barrel, a spring for yieldably pressing said piston downward, a nozzle telescopically engaging the portion of reduced diameter and forming a stop for said piston, and a hollow connecting rod for drawing downward said nozzle upon the opening of the throttle, thereby withdrawing the stop and permitting the spring pressed plunger to eject fuel through the nozzle, said rod also constituting a fuel passage from the nozzle which registers with a port through the throttle in the idling position of the latter.
- 40 11. A carburetor comprising a downwardly directed mixture inlet, a throttle valve controlling the same, a casing above said inlet having a cylindrical barrel portion and a portion of reduced diameter depending therefrom into said inlet, a piston in said barrel, a spring for yieldably pressing said piston downward, a nozzle telescopically engaging the portion of reduced diameter and forming a stop for said piston, a needle valve cooperating with said nozzle to form a metering device and a hollow connecting rod for drawing downward said nozzle upon the opening of the throttle to withdraw said stop and to permit the spring pressed plunger to eject fuel through the nozzle under variable restriction of said needle valve, said connecting rod also forming the fuel passage from the nozzle which in the 45 50 55 60 65 70 75
- idling position of the throttle registers with a port therethrough.
12. A carburetor comprising a throttle, a downwardly directed mixture inlet, a throttle valve therein, a casing above said inlet having a cylindrical barrel portion and a depending portion of reduced diameter extending into said inlet, a piston in the barrel portion of said casing, a spring for pressing said piston downward, a nozzle slidably engaging the portion of reduced diameter and forming a stop for the piston, a needle valve co-operating with said nozzle, a connecting rod between said nozzle and said throttle for drawing downward the nozzle when the throttle is open, and an adjustable connection between said mixture inlet and said casing for varying the restriction of said needle valve.
- 80 85 90 95 100 105 110 115 120 125 130 135 140 145 150 155 160
13. A carburetor comprising a throttle, a casing forming a downwardly directed Venturi inlet passage, a throttle valve controlling said passage, a bell shaped casing above said first mentioned casing and overlapping the same to form therewith a return bent air inlet, a casing centrally depending from said bell shaped casing having a barrel portion and a portion of reduced diameter extending downward into said Venturi inlet, a piston in said barrel, a tubular stem in said piston, a spring for yieldably pressing said piston downward, a nozzle slidably in said portion of reduced diameter and forming a stop for said tubular stem, a needle valve in said tubular stem co-operating with said tubular stem and nozzle to variably restrict the passage of fuel therethrough, and a hollow connecting rod for drawing downward said nozzle by the opening of said throttle forming a fuel passage from said nozzle which in the idling position of the throttle registers with a port therethrough and in the open position of the throttle is cut off from communication with said port.
14. A carburetor comprising a casing forming a downwardly directed Venturi shaped mixture inlet, a throttle valve therein, a bell shaped casing above and overlapping said first mentioned casing to form in connection therewith a return bent air inlet, a casing depending centrally from said bell shaped casing having a barrel portion and a portion of reduced diameter extending downward into said Venturi passage, a loose fitting plunger in said barrel, a tubular stem for said plunger, a spring for pressing said plunger downward, a needle valve in said tubular stem, a member for supporting said needle valve in said tubular stem, and an abutment for said spring, a nozzle telescopically engaging said portion of reduced diameter forming a stop for said tubular stem and cooperating with said needle valve to variably restrict the flow of fuel, a mechanical connection for drawing down said nozzle upon the opening of said throttle, a cup shaped piston engaging said barrel and normally supported by said nozzle to be slightly spaced from said plunger and to provide a passage therebetween for the flow of fuel and an annular bearing on said plunger for sealing against said piston when said nozzle is depressed to positively eject the fuel through said nozzle.
15. A carburetor comprising a mixture inlet, a throttle valve controlling the same, a casing having a cylindrical barrel portion containing liquid fuel and a portion of reduced diameter extending therefrom into said inlet, a piston in said barrel, a spring for yieldably pressing said piston to discharge the liquid, a nozzle telescopically engaging the portion of reduced diameter and 150

forming a stop for said piston and a mechanical connection between said nozzle and throttle for withdrawing the stop as the throttle is opened.

16. In a carburetor, the combination with a mixture inlet, of a throttle valve therein, a casing containing liquid fuel, a piston for displacing the fuel from said casing, a tubular shank for said piston through which the liquid fuel is displaced, a nozzle telescopically engaging said tubular shank and mechanically connected with said throttle, said nozzle forming a stop for said piston in the idling position of said throttle, a spring acting upon said piston in the direction of said stop and a stationary needle valve cooperating with said tubular shank to variably restrict the flow of fuel therethrough whereby the opening of said needle valve is proportional to the displacement of said piston and the latter is proportional to the opening of the throttle.
